UNITED STATES PATENT OFFICE.

ALBERT L. DUFF AND JAMES WM. MATHESON, OF BROOKLYN, NEW YORK; SAID DUFF
ASSIGNOR TO SAID MATHESON.

WARDROBE TRUNK.

Application filed January 10, 1922. Serial No. 528,252.

To all whom it may concern:

Be it known that we, ALBERT L. DUFF and JAMES W. MATHESON, citizens of the United States, and residents of the city of New York, borough of Brooklyn, in the county of Kings and State of New York, have invented a new and Improved Wardrobe Trunk, of which the following is a description.

The general object of our invention is to 10 provide a unitary trunk body, free from the weakness of a body composed of hinged sections and having a chest of drawers of desirable capacity as well as characterized by ample garment hanging space and provided 15 with a convenient arrangement of garment supporting means.

A further object of our invention is to provide novel garment-supporting means particularly adapted for a unitary trunk 20 body as characterized above and whereby to attain the maximum accessibility of the hung garments and promote convenience in the hanging and removal of the garments.

The invention contemplates also clamping 25 means for the hung garments coordinated with the novel garment supporting means referred to.

The invention furthermore has for an 30 object to provide a unitary trunk as characterized having a vertical partition between the chest of drawers and the garment-hanging space and to provide swinging doors of which one is adapted to close over the chest of drawers and arranged to be locked 35 to the partition in a manner that the chest of drawers may remain covered by its door and the latter locked while leaving the door in front of the garment-hanging space free to be opened or closed, as desired.

40 The manner and means whereby the above and other objects are attained will be clear from the detail description following.

Reference is to be had to the accompanying drawings forming a part of this specification, it being understood that the drawings are merely illustrative of one example of the invention.

Figure 1 is a perspective view of a wardrobe trunk embodying our invention, the 50 doors being shown open;

Figure 2 is a transverse vertical section through a portion of the chest of drawers as indicated by the line 2-2, of Figure 1;

Figure 3 is a horizontal section taken 55 above the garment supporting means;

Figure 4 is a front elevation of the guard constituting the backboard of the garment-supporting means;

Figure 5 is a vertical section through the supporting means as indicated by the line 5-5, Figure 4;

Figure 6 is a fragmentary sectional plan view of the trunk, the section being taken through the garment-hanging space above the clamping means;

Figure 7 is a fragmentary vertical section showing the garment-supporting means and the track rails therefor in side elevation;

Figure 8 is a vertical section as indicated by the line 8-8, Figure 1;

Figure 9 is a fragmentary perspective view showing the locking means for that door covering the chest of drawers;

Figure 10 is a vertical section on the line 10-10, Figure 9;

Figure 11 is perspective view of one end of one of the garment clamping bars;

Figure 12 is a side elevation of modified wheels and tracks for the backboard carriage;

Figure 13 is a fragmentary perspective view given to show a modified form of the elements adapted to form extensions of the track rails and constituting a support for the garment-supporting means.

In carrying out our invention in accordance with the illustrated example, a single box-like body 10 is provided having a vertical partition 11 at approximately the medial plane of the body. At one side of the partition is a chest of drawers 12 separated by horizontal partitions 13, the body at the opposite side of the partition 11 affording a space 14 for hung garments. At the bottom of the body the same is given the form of a shallow box 15 for shoes, etc., said box having a slide cover 16 in the clothes hanging compartment 14.

The front of the body is closed by a suitable door or doors; advantageously a pair 100 of doors 17 is provided which are of L-form being provided with rearwardly directed extensions 17^a hinged at their rear edges as at 18 and forming part of the sides of the trunk when the doors are closed. At the 105 same time the form of the doors and their hinging rearward of the plane of the trunk front increases the front opening and the accessibility of the trunk when the doors are opened.

To lock that door 17 which is adapted to fold against the front of the chest of drawers 12 we provide a locking means as follows: On the partition 11 adjacent to the 5 front edge is a lock 20 here conventionally shown and in practice of any approved form, the numeral 19 indicating the escutcheon. On the door which closes over the drawers 12 at the inner side of said 10 door, we provide a hinge element 21 having at its lower edge a laterally directed flange 22 adapted to extend into a transverse slot 23 in the partition 11 above the lock 20, said flange having a vertical hole 22^a adapted 15 to receive the bolt 20^a of lock 20. For locking the two outer doors together any suitable locking means may be employed, there being conventionally indicated in the present example a known form of trunk lock 24.

In the garment hanging compartment 14 near the top, we provide on the partition 11 and on the body at the opposite side of said compartment pairs of upper and lower 25 track rails 25 on which travels a carriage having in the illustrated form side members in the form of plates 26 equipped with wheels 27 to run respectively on the top of the upper rails and at the under side of the 30 lower rails 25, the arrangement of the wheels preventing tilting of the carriage on the track under the weight of the hung garments. The opposite side members 26 are connected by the backboard 28 of the garment-supporting means. Said backboard in the present instance is formed from a channel bar, the flanges projecting forwardly and the ends 29 of the back of said channel bar extending through the side members 35 and being disposed between the upper and lower track rails 25 of a pair as will be clear from Figures 4, 5 and 7. The backboard 28 is equipped with a series of hanger arms 30 disposed in pairs as is customary in wardrobe trunks, so that a garment may be clamped between the arms of a pair. The inner ends of the supporting arms 30 are suitably pivoted for lateral swinging movement there being shown straps 31 on the rear ends of the arms extending about vertical pivot pins 32 riveted to the upper and lower flanges of the channel backboard 27. The arms 30 are provided with means to suspend the clothes hangers A which may be of any approved type, there being in the illustrated form a loop 34 rigid on one of the arms 30 of each pair in which loop the hanger hook a is adapted to engage.

At the front ends of the rails 25 we provide auxiliary rail sections 35 suitably pivoted at their inner ends as at 36 to be swung to positions extending forwardly to constitute extensions of the rails 25 beyond the trunk body or to fold to inner positions athwart the space 14. In the inner posi-

tions the overlapped rail sections 35 are secured to each other by suitable fastening means which may, as shown, consist of a bolt 37 on one arm 30 of a pair and a wing nut 38 on said stud. The arms 30 of a 70 pair have suitable clamp means, there being shown a bolt 30^a on one arm of a pair and a turnable head 30^b on said stud adapted in one position to pass through a slot 30^c in the other arm of the pair and be turned through 75 90° for clamping.

In order to limit the outward movement of the backboard 28, we provide on each of the extension track sections 35 at the under side a depending stop lug 47, and it will be 80 observed from Figure 5 that the forward one of the lower wheels 27 is set back from the plane of the upper forward wheel to engage the stop at a proper point.

A modification of the wheeled structure 85 and tracks is shown in Figure 12 in which track rails 25^a are employed engaging toothed wheels 27^a on the side members 26^a appurtenant to the backboard 28^a.

In order to strengthen the trunk at the 90 front corners and provide a resistance to any undue pressure or blow exerted on the doors 17, we provide vertical members 48 preferably in the form of metal rods located forwardly of the hinges 18 so as to lie in the 95 entrant angles of the doors when closed.

A modification of the rail extensions 35 is shown in Figure 13 in which the extensions designated 35^a are connected to the main rails 25 by pivots 36 as in the first- 100 described arrangement. In the form shown in Figure 13, the rail sections 35^a instead of merely overlapping at the center as in the first-described arrangement, extend from one side rail 25 to a point adjacent to the opposite side rail 25. In the larger trunks the rail sections 35 that overlap at the medial plane of the hanger space 14 will suffice because affording the necessary extensions of the rails 25 to permit the arms 105 30 and the backboard of the guard wheels to move outward a sufficient distance for the convenient manipulation of the arms 30 in placing and removing the garments. In small trunks, however, the reduced width 110 of the space 14 makes it desirable that the track rail sections 35^a extend each the full width of the hanger space in order to afford the necessary extension of the side rails 115 25.

In the inner transverse or nested position of the rail sections 35 or 35^a, said rail sections constitute a supporting means for the outer ends of the garments supporting arms 30 when the latter are in the inner position 125 within the trunk body and relieve the pivots 32 of the weight of the hung garments. The pairs of arms may be used not only for the clamping of garments therebetween in addition to the garments on the hangers A 130

but also the garments may be thrown over the arms or additional hangers hooked over the tops of the arms.

It is to be noted that the rigid trunk body accommodating the drawers 12 at one side and affording a hanger space at the other side is unsuited to ordinary garment-supporting means looking to a reasonable capacity. Our described garment-hanging means can be made to include a sufficient number of hanger arms to support a large number of garments and meet the requirements of the trade and trunk users. It will be observed that the arms 30 are disposed, when in the trunk, lying perpendicular to the plane of the trunk front or approximately so and that the backboard carrying the arms has a parallel movement to or from the front of the trunk, the arms 30 moving, with the backboard, straight into and out of the trunk endwise, the movement being parallel with the sides of the drawers 12.

The available garment hanging space in a trunk of this general type is largely reduced due to the fact that the space is narrow owing to the presence of the drawers. In providing the improved garment supporting means as described the garment-hanging space is availed of to the maximum extent. At the same time the arrangement of the garment supporting arms and their disposition and direction of movement coupled with the provision for projecting them in a straight line beyond the front, makes the accessibility of the hung garments and the capacity of the supporting means all that can be desired, while retaining the recognized superiority of the rigid trunk body with respect to strength. Another advantage of the described arrangement of a trunk constructed as described is that with the garment supporting arms carried to the outer position, they may be spread more or less into fan-like form and largely within the planes of the sides of the trunk because the arms may be folded laterally at that side having the drawers so that the spread arms need not project at all or at least project to the minimum extent laterally at that side of the trunk remote from the drawers and thereby little space need be available at a side of the trunk for the swinging of the arms in situations where room space is limited.

The disposition of the garments when suspended from the particular supporting means described prevents the use of the usual clamping means provided in wardrobe trunks below the hangers for exerting pressure on or clamping the garments below, for which reason we provide special garment clamping means coordinated with the described garment-supporting means, said clamping means comprising clamp bars

40 at least two in number, to coact in clamping a series of garments at the opposite sides. The bars 40 extend in a direction from front to rear, that is to say, parallel with the positions and directions of movement of the supporting arms. The ends of the bars 40 have hooks 40^a thereon directed downwardly and each adapted to engage in a series of vertical holes 41 in a fixed bar 42 in the space 14 at the back and adapted to engage at their front ends in similar holes 43 in bar sections 44 which are hinged at their remote ends as at 45 to the partition 11 and to the opposite wall of the space 14. The bar sections 44 are adapted to overlap, one overlapping end having a bolt 46 receiving a wing nut 47 or its equivalent. Thus, the sections 44 may be raised to the supporting position and held together, or unfastened and permitted to drop to the dotted line position shown in Figure 1 when when the garment supporting means above is to be moved outwardly to carry the garments beyond the trunk.

We would state in conclusion that while the illustrated example constitutes a practical embodiment of our invention, we do not limit ourselves strictly to the exact details herein illustrated, since, manifestly, the same can be considerably varied without departure from the spirit of the invention as defined in the appended claims.

Having thus described our invention, we claim:

1. In a wardrobe trunk, garment-supporting means including a backboard approximately parallel with the front and back of the trunk, and movable therein toward or from the front, supporting arms mounted on said backboard to move bodily therewith and extending forward therefrom to be projected beyond the front of the trunk in the forward position of the backboard, and means adapted to be positioned across the garment-hanging space at the front of the trunk to constitute a support for the forward ends of said supporting arms when the trunk is closed.

2. In a wardrobe trunk, a backboard, a series of garment-supporting arms on said backboard and extending forward therefrom, main rails within the trunk, wheeled supports for said backboard adapted to travel on said rails, and auxiliary rail sections pivotally mounted to assume positions in line with the first mentioned rails, or to lie transversely in the trunk, said rail sections in the transverse positions constituting a support for the outer ends of said garment-supporting arms when the backboard is moved to the inner position.

3. In a wardrobe trunk, a backboard, a series of garment-supporting arms on said backboard and extending forward therefrom, side rails, wheeled supports for said

1 backboard and movable on said rails, auxiliary rail sections pivotally mounted to assume positions in line with the first mentioned rails or to lie transversely in the 6 trunk, and means to fasten the auxiliary rail sections to each other when disposed transversely.

4. In a wardrobe trunk, vertical side wall members bounding the garment hanging 10 space, a pair of horizontal rails fixed upon each side wall, a wheeled carriage mounted to roll on said rails toward and from the back wall of the trunk, supporting arms carried by said carriage, and stop means at the 15 forward ends of the rails to limit the forward movement of the carriage and arms, said stop means including pivoted auxiliary front end sections of the rails, the lower auxiliary rail of each pair having a down- 20 wardly extending lug against which a portion of the carriage is adapted to strike.

5. In a wardrobe trunk, a garment supporting carriage movable toward and from the rear wall of the trunk, said carriage 25 comprising a pair of vertical side plates, a backboard having its ends projected through and interlocked in said side plates, support-

ing wheels journaled on the side plates, garment supporting means attached to and extending forward from the backboard, and 30 means attached to the side walls of the trunk for supporting the wheels.

6. Mechanism as set forth in claim 5 in which the vertical side plates of the carriage are of sheet metal and provided 35 with vertical slits and the backboard is of channel form having flat end members projected through said slits, and the garment supporting means is secured to the backboard between the upper and lower flanges 40 of the channel construction.

7. Mechanism as set forth in claim 5 in which the backboard is of channel formation having upper and lower horizontal flanges and the garment supporting means comprises a series of pairs of clamping arms pivotally mounted between the backboard flanges on vertical pivots, the arms of each pair being movable toward and from each other at their front ends and having means 45 to fasten the front ends thereof together.

ALBERT L. DUFF.
JAMES WM. MATHESON.
